CLAIM

The ornamental design for a shoe as shown and described.

DESCRIPTION

FIG. 1 is a front perspective view of a shoe showing my new design;
FIG. 2 is a side view thereof;

FIG. 3 is an opposite side front perspective view thereof;

FIG. 4 is an opposite side view thereof; and,

FIG. 5 is a top view thereof.

The even-length broken lines represent stitching that forms no part of the claimed design. The uneven-length broken line showing of the four circular shaped elements represent eyelets that form no part of the claimed design. The uneven-length broken lines depicting the remainder of the shoe form no part of the claimed design.
